UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 8, 1920. Serial No. 408,851.

To all whom it may concern:

Be it known that I, ALBEN E. LUNDELL, a citizen of the United States, residing at New York, in the county of New York and State 5 of New York, have invented certain new and useful Improvements in Telephone-Exchange Systems, of which the following is a full, clear, concise, and exact description.

This invention relates chiefly to automatic telephone exchange systems and more particularly to an automatic exchange system of large capacity.

In an automatic exchange system arranged for serving a large number of subscribers' 10 lines, it is usual to set a train of switches to establish the connection between the calling and the called subscribers. The first switch to be operated is usually utilized to select the particular district in which the called 15 subscriber's line is located. In smaller systems, the first switch of the train is used to select the exchange in which the called subscriber's line is located. Since outlying districts and distant exchanges are at varying 20 distances from the first switch, trunk lines of different lengths must be employed. These trunk lines will have various degrees of "loading." This "loading" as it is termed, consists of connecting coils having 25 suitable impedance characteristics into the circuits of the trunks to improve the transmission qualities when the first switch in the train is provided with a repeating coil. It is necessary that the ratio of the number of 30 turns in the primary and secondary windings of such repeating coil be made variable, in order to accomplish good transmission.

It is the object of this invention to provide novel and simple means for selecting a 35 suitable number of turns on the secondary winding of a repeating coil so that the ratio of the turns on the secondary winding to the number of turns on the primary winding will be of a correct value to provide proper 40 transmission on any trunk to which the switch, with which the repeating coil is associated, has access.

In previous systems in which means have 45 been provided for varying the ratio of the repeating coil windings, the result has been accomplished under the control of the sender as a result of a selective operation of an automatic switch. This type of operation places an additional burden on the 50 sender, since it tends to complicate the

sender circuits and also requires an additional time interval in which to accomplish the extra selective operation.

It is a further object of the invention to provide a system in which the ratio of the 60 windings of a repeating coil associated with an automatic switch may be varied in accordance with distinctive electrical characteristics of the trunks to which it has access.

A system in which the characteristics of the trunks themselves determine the repeating coil ratio has additional advantages over a system in which the selection of ratio is 65 accomplished under the control of a sending device. If a change of routing is desirable it may follow that the loading of the trunk must be varied. If the selection is under the control of the sender, re-design and re-wiring of all senders may be necessary in order to accomplish such change of 70 routing.

A feature of the invention is the use of relays to whose contacts the secondary windings of a repeating coil are connected in such 75 a manner that the number of effective turns of the winding may be variably controlled in accordance with the relay combination which has been actuated.

A further feature of the invention resides 80 in the means for controlling the above mentioned selecting relays by means of distinctive potentials found on the terminals of the trunk selected.

An additional feature of the invention is 85 an arrangement whereby the trunk conductors are placed in their normal talking condition by the removal of the distinctive electrical characteristics at the proper stage in the progress of the connection.

It is thought that the invention will best 90 be understood from the following detailed description, reference being made to the accompanying drawing.

In the drawing the figure shows so much 95 of a telephone system as is necessary to an understanding of the invention. The invention has been shown applied to a semi-automatic system employing power driven switches, but since it is obviously capable of 100 adaptation to many types of telephone systems it is not to be limited to the system as disclosed.

The operation of the system is as follows. 105 When the subscriber at the substation 1 110

removes his receiver from the switch hook, a circuit is completed from grounded battery, left hand winding of line relay 2, outer armature and back contact of cutoff relay 3, 5 through the closed loop of the calling subscriber's line, inner armature and back contact of relay 3, right hand winding of line relay 2 to ground. Relay 2 is energized and completes a circuit from grounded battery, 10 lamp 4, right hand armature and front contact of relay 2 to ground. The resultant illumination of lamp 4 informs the operator that the associated line is calling. She thereupon inserts answering plug 5 into 15 jack 6 whereupon a circuit is completed from grounded battery, winding of relay 7, sleeve contacts of plug 5 and jack 6, winding of cutoff relay 3 to ground. Relays 7 and 3 are energized in this circuit. Relay 20 3, upon energizing, opens the circuit of line relay 2 and this relay de-energizes, causing lamp 4 to be extinguished.

The operator then depresses listening key 8 whereupon her telephone head set is connected to the calling line. The calling subscriber may now converse with the operator and inform her of the number of the wanted line.

The cord circuit used by the operator terminates at one end in an answering plug and in the other in an automatic switch. In order to simplify the disclosure, it has been assumed that the switch shaft has mounted upon it but one set of brushes and that this 30 set of brushes serves a contact bank containing the terminals of 100 trunk lines arranged in 10 groups of 10 trunks each. The mechanical structure of the switch is a readily understood simplification of the 500 point switch shown in Patent No. 1,123,696 issued January 5, 1915, to E. B. Craft and J. N. Reynolds.

The operator, upon ascertaining the number of the wanted line, depresses keys in a 45 key set (not shown) to control the sender shown within the dotted rectangle at the bottom of the drawing. In practice this sender would be associated with the desired cord circuit by means of a cord finder. The 50 cord finder and key set have been omitted since they are well known in the art, Patent No. 1,168,819 issued January 18, 1916, to A. E. Lundell shows complete circuits for controlling a sender of the type which is 55 diagrammatically indicated in the drawing of the present invention.

When the sequence switch (not shown) associated with the sending device, and which controls sequence switch contacts 9 60 and 10, reaches position 2, a circuit is completed from grounded battery, winding of relay 11, lower right hand contact of sequence switch spring 12, conductor 13, winding of stepping magnet 14, contact of sequence switch spring 10, armature and back

contact of the 0' counting relay, conductor 15, lower contact of sequence switch spring 16 to ground. Relays 11 and 14 are energized in this circuit and relay 11, upon energizing, locks up through its left-hand armature and front contact and the lower left-hand contact of sequence switch spring 12 to grounded conductor 13.

Relay 11 at its right hand armature and front contact completes a circuit from 75 grounded battery power magnet of sequence switch 17, lower contact of sequence switch spring 18, right hand armature and front contact of relay 11 to ground, for moving this sequence switch out of position 1 and 80 into position 2.

In position 2 of sequence switch 17 a circuit is completed from grounded battery, winding of the up drive magnet 19, lower 85 contact of sequence switch spring 20, right hand armature and front contact of relay 11 to ground. The energization of magnet 19 causes the brush shaft to be moved upwardly. As soon as commutator brush 21 90 engages the first conducting segment of commutator 22 a circuit is completed from grounded battery, winding of relay 11, left hand armature and front contact of relay 11, left hand contacts of sequence switch 95 spring 12, conductor 23, commutator brush 21 to ground. Stepping magnet 14 is shunted down due to the fact that relay 11 has now found a direct path to ground. As the brush shaft is moved upwardly relay 14 is intermittently energized to control the operation of the counting relays in the well known manner. When the 0' counting relay is energized the circuit through stepping magnet 14 is permanently opened and when, a moment later, commutator brush 21 engages an insulating segment of commutator 22, relay 11 is de-energized and completes a 100 circuit from grounded battery power magnet of sequence switch 17 the upper contact of sequence switch 18, the right hand armature and back contact of relay 11 to ground for moving this sequence switch out of position 2 and into position 3. The deenergization of relay 11 also opens the circuit of up drive magnet 19, thus causing the brush shaft to 105 come to rest with the brush set engaging the contact set of the first trunk in the selected group.

It will be assumed that the third group of trunks has been selected. If the first 110 trunk in this group is busy this fact will be indicated by the presence of ground potential on the test terminal of such trunk. A circuit is thereupon completed from grounded battery, winding of relay 11, contact of sequence switch spring 27, test brush 25, test terminal 26, and thence to ground by way of a sequence switch contact, corresponding to contact 27, associated with the switch which has seized such trunk. Relay 11 is 115 120 125 130

energized in this circuit and completes a circuit from grounded battery, winding of up-drive magnet 19, lower contact of sequence switch spring 20, right-hand armature and 5 front contact of relay 11 to ground. The brush shaft is now again moved upwardly in a trunk hunting movement. As soon as test brush 25 engages, test terminal 28, which will be assumed to be the first idle trunk in 10 the group, relay 11 deenergizes, since no ground potential is found on such test terminal. The deenergization of relay 11 opens the circuit of up-drive magnet 19, and causes the brush set to be brought to rest on the 15 terminals of the idle trunk. The deenergization of relay 11 also completes a circuit extending from grounded battery, power magnet of sequence switch 17, upper contact of sequence switch spring 18, right-hand armature and back contact of relay 11 to ground, for moving this sequence switch out of position 20 4 and into position 10.

As soon as sequence switch 17 reaches position 43, ground potential is supplied to 25 test terminal by way of test brush 25 at the lower contact of sequence switch spring 27 to render the trunk non-selectable to other hunting selector switches.

As soon as sequence switch 17 reaches 30 position 7, a circuit is completed from grounded battery, high resistance winding of relay 24 upper armature and back contact of relay 29, terminal 30, brush 31, conductor 32, lower contact of sequence switch 35 spring 33; winding of marginal relay 34 to ground. Due to the fact that battery has been supplied to the tip conductor of the trunk through a high resistance, marginal relay 34 does not operate. Since no potential is found on the ring conductor of 40 the trunk, marginal relay 35 cannot be operated.

Relay 24 is energized in the circuit above traced and completes a circuit from 45 grounded battery, winding of relay 36, armature and front contact of relay 24 to ground. Relay 36 is energized in this circuit and locks up to grounded test terminal.

As soon as sequence switch 17 leaves position 50 8, relay 24 is deenergized and completes a circuit extending from grounded battery, winding of relay 29 armature and back contact of relay 24 armature and front contact of relay 36 to grounded test terminal. Relay 29 is energized and by attracting its armatures connects through the tip and ring conductors to the main tip and ring conductors 37 and 38 of the selected trunk.

Sequence switch 17 comes to rest in position 60 10 and the fundamental circuit is now extended to the succeeding switch in the train. The fundamental circuit may be traced from trunk conductor 37, upper armature and front contact of relay 29, terminal 30, brush 31, upper right-hand contact of sequence

switch spring 12, conductor 13, winding of stepping magnet 14, contact of sequence switch spring 10, armature and back contact of the 0' counting relay, conductor 15, upper contact of sequence switch 16, brush 39, terminal 40, lower armature and front contact of relay 29, ring trunk conductor 38. Succeeding switches in the train are actuated in the well-known manner under the control of the sender. The completion 75 of each selective operation will cause the advance of the sender sequence switch. When the sender sequence switch reaches position 14, at which time it will be assumed that all the selective operations have been 80 completed, a circuit is completed from grounded battery, power magnet of sequence switch 17, upper left-hand contact of sequence switch spring 41, contact of sequence switch spring 9 to ground for moving this sequence switch out of position 10 and into position 16.

In position 16 of sequence switch 17, the talking connection is completed at the district switch by means of closures at sequence switch springs 33 and 42. Assuming that the called subscriber has answered, supervisory relay 43 will have been energized. The circuit of the secondary winding of the district 90 repeating coil may then be traced from grounded battery, winding of supervisory relay 44, lower right-hand winding of repeating coil 45, it being observed that a maximum number of turns are included, inner lower armature and back contact of 95 relay 34, contact of sequence switch spring 42, brush 39, terminal 40, lower armature and front contact of relay 29, trunk conductor 38, lower left-hand winding of repeating coil 46, armature and front contact of relay 43, resistance 47, upper left-hand winding of repeating coil 46, trunk conductor 37, upper armature and front contact of relay 29, terminal 30, brush 31, conductor 32, upper contact of sequence switch 100 spring 33, upper armature and back contact of relay 34, upper right-hand winding of repeating coil 45 to ground.

It is to be observed that the selection of a trunk in the third group, which is characterized by having reduced battery potential supply to the tip conductor of the trunk, will result in the selection of the maximum ratio of the number of turns in the secondary winding of repeating coil 45, to those in the primary winding.

The connection having been completed the subscribers may now converse, it being noted that calling supervisory relay 48 was 115 energized when the operator first inserted plug 5 into jack 6.

When connection is no longer desired, both calling and called subscribers will replace their receivers on their switch-hooks. The 120 replacement of the calling subscriber's re-

ceiver causes the deenergization of relay 48 and the replacement of the called subscriber's receiver results in the deenergization of relay 43. The deenergization of relay 43 causes in turn the deenergization of relay 44. The operation of the supervisory signals not shown controlled by relays 48 and 44 respectively informs the operator that connection is no longer desired and she thereupon removes plug 5 from jack 6.

The removal of plug 5 from jack 6 interrupts the circuit of relay 7 and this relay deenergizes and completes a circuit from grounded battery, power magnet of sequence switch 17, lower contact of sequence switch spring 41, armature and back contact of relay 7 to ground, for moving this sequence switch out of position 16 and into position 18.

20 In position 18 of sequence switch 17 a circuit is completed from grounded battery, winding of down drive magnet 49, contact of sequence switch spring 50 to ground. The brush shaft is returned to its normal position under the control of magnet 49 and as soon as commutator brush 21 engages normal commutator segment 51, a circuit is completed from grounded battery, winding of power magnet of sequence switch 17, upper right-hand contact of sequence switch spring 41, commutator segment 51, commutator brush 21 to ground, for moving sequence switch 17 out of position 18 and into position 1.

35 As soon as the brush set leaves the terminals of the trunk, the release of the succeeding switches in the train takes place in the well-known manner.

40 The operation of the system if connection to a trunk in the second group is desired will now be described. In this case the operation of the system will be identical with that previously described up to the selection of an idle trunk in the second group. Sequence switch 17 will then be moved out of position 4 as previously described.

45 As soon as sequence switch 17 reaches position 7 a circuit is completed from grounded battery, low resistance winding of relay 60, upper armature and back contact of relay 61, terminal 62, brush 31, conductor 32, lower contact of sequence switch spring 33, winding of relay 34 to ground. Since the winding of relay 60 is of low resistance, 50 marginal relay 34 is energized in this circuit. Relay 60 is also energized. Relay 34, upon energization, completes a locking circuit for itself extending from ground, winding of relay 34, outer lower armature and front 55 contact of relay 34, contact of sequence switch spring 63 to grounded battery. The energization of relay 60 completes a circuit for sleeve relay 64, and this relay locks up to grounded test brush 25 in the same 60 manner as relay 36, associated with the third

group trunk was energized. As soon as sequence switch 17 leaves position 8, the circuit of relay 60 is opened and this relay deenergizes, allowing relay 61 to be energized over a circuit extending from grounded battery, winding of relay 61, armature and back contact of relay 60, armature and front contact of relay 64 to ground at test brush 25. The energization of relay 61 connects through the tip and ring conductors to the succeeding switch, which is then controlled over the fundamental circuit as soon as sequence switch 17 reaches position 10.

65 After all the switches have been set and the district sequence switch is advanced into position 16, the talking circuit is completed. It is to be noted that since relay 34 is now energized, the secondary winding of the repeating coil is connected to the tip and ring conductors of the link circuit by way of the back contacts and armatures of relay 35 and the front contacts and armatures of relay 34. An inspection of the drawing will show that a different number of turns has now been included in the secondary winding of the repeating coil than were previously utilized.

70 It is thought that the operation and possibilities of the system will be readily understood without further description. An inspection of the arrangement of the electrical devices associated with the trunks in the first group show that if a trunk in this group is seized, battery will be supplied to both relays 34 and 35 through the low resistance winding of relay 65. In this case 75 both relays 34 and 35 will be energized and locked up and a third repeating coil ratio 80 will be obtained.

85 It is to be noted that the system is not limited to use in connection with automatic exchange systems but may be employed wherever a connecting link circuit, with which 90 a repeating coil is associated, is used.

95 What is claimed is:

1. In a telephone exchange system, incoming lines, outgoing lines, a link circuit to be 100 used in establishing a connection between an incoming line and an outgoing line, a repeating coil associated with said link circuit, said repeating coil comprising a primary winding and a secondary winding, means for varying the ratio of the number of turns of said 105 secondary winding to the number of turns of said primary winding, and means associated with said outgoing lines to cause the 110 operation of said ratio varying means.

115 2. In a telephone exchange system, incoming lines, outgoing lines, a link circuit to be used in establishing a connection between an incoming line and an outgoing line, a repeating coil associated with said link circuit, said repeating coil comprising a primary winding and a secondary winding, means for selectively controlling the 120 ratio of the number of turns of said sec- 125

ondary winding to the number of turns of said primary winding, and means associated with said outgoing lines to cause the operation of said ratio controlling means in accordance with the character of said outgoing lines.

3. In a telephone exchange system, incoming lines, outgoing lines, a link circuit terminating at one end in an automatic switch, means to operate said automatic switch to establish connection between an incoming line and an outgoing line, a repeating coil associated with said link circuit, said repeating coil comprising a primary winding and a secondary winding, means for selectively controlling the ratio of the number of turns of said secondary winding to the number of turns of said primary winding, said means associated with said outgoing lines to cause the operation of said ratio controlling means.

4. In a telephone exchange system, incoming lines, outgoing lines, electrical devices associated with said outgoing lines, there being differing electrical devices associated with different outgoing lines, a link circuit to be used in establishing a connection between an incoming line and an outgoing line, a repeating coil associated with said link circuit, said repeating coil comprising a primary winding and a secondary winding, electro-mechanisms selectively responsive to said electrical devices when connection is established between said link circuit and an outgoing line, and means for varying the ratio of the number of turns of said secondary winding to the number of turns of said primary winding in accordance with the response of said electro-mechanisms.

5. In a telephone system, a switching device comprising a set of movable contacts and a plurality of sets of stationary contacts, a link circuit terminating in said movable contact set, a plurality of outgoing lines terminating in said stationary contact sets, means to supply various combinations of potentials to said stationary contacts, a repeating coil associated with said link circuit, said repeating coil comprising a primary winding and a secondary winding, and means variably responsive to said combinations of potentials to vary the ratio of the number of turns of said secondary winding to the number of turns of said primary winding.

6. In a telephone exchange system, a switching device comprising a set of movable contacts and a plurality of sets of stationary contacts, a link circuit terminating in said movable contact set, a plurality of outgoing lines terminating in said stationary contact sets, means to supply various combinations of potentials to said stationary contacts, a repeating coil associated with said link circuit, said repeating coil comprising a pri-

mary winding and a secondary winding, means responsive to said various combinations of potentials to vary the ratio of the number of turns of said secondary winding to the number of turns of said primary winding, means to remove said combinations of potentials from a contact set with which connection has been established, and means to maintain a selected ratio effective irrespective of the condition of said stationary contacts.

7. In a telephone exchange system, a switching device comprising a movable contact set and a plurality of sets of stationary contacts, a link circuit terminating at one end in said movable contact set, a repeating coil associated with said link circuit, said repeating coil comprising a primary winding and a secondary winding, a plurality of outgoing lines terminating in said stationary contact sets, means to supply different combinations of potentials to said stationary contact sets to characterize said outgoing lines, and means variably responsive to said combinations of potentials to vary the ratio of the number of turns of said secondary winding to the number of turns of said primary winding when connection is established from said link circuit to an outgoing line by means of said switching device.

8. In a telephone exchange system, incoming lines, outgoing lines, means to supply potentials to the conductors of said outgoing lines, there being differing combinations of effective potentials associated with different outgoing lines, a link circuit to be used in establishing a connection between an incoming line and an outgoing line, a repeating coil associated with said link circuit, said repeating coil comprising a primary winding and a secondary winding, relays selectively responsive to said combinations of potential when a connection is established between said link circuit and an outgoing line, and means for varying the ratio of the number of turns of said secondary winding to the number of turns of said primary winding in accordance with which ones of said relays have been actuated.

9. In a telephone exchange system, incoming lines, outgoing lines, means to supply potentials to the conductors of said outgoing lines, there being differing combinations of effective potentials associated with different outgoing lines, a link circuit to be used in establishing a connection between an incoming line and an outgoing line, a repeating coil associated with said link circuit, said repeating coil comprising a primary winding and a secondary winding, relays selectively responsive to said combinations of potentials when connection is established between said link circuit and an outgoing line, locking circuits for said relays, and means for varying the ratio of the number of turns

- 6
- of said secondary winding to the number of turns of said primary winding, in accordance with which ones of said relays have been actuated.
5. 10. In a telephone exchange system, incoming lines, outgoing lines, means to supply potentials to the conductors of said outgoing lines, there being differing combinations of effective potentials associated with 10 different outgoing lines, a link circuit to be used in establishing a connection between an incoming line and an outgoing line, a repeating coil associated with said link circuit, said repeating coil comprising a primary winding and a secondary winding, marginal relays selectively responsive to said combinations of potential when a connection is established between said link circuit and an outgoing line, and means for varying the 15 ratio of the number of turns of said secondary winding to the number of turns of said primary winding in accordance with which ones of said relays have been actuated.
15. 20. In a telephone exchange system, a switching device comprising a set of movable contacts and a plurality of sets of stationary contact sets, a link circuit terminating in said movable contact set, a plurality of outgoing lines terminating in said stationary contact sets, a group of relays associated with each outgoing line, means comprising windings and contacts of said relays to supply potentials to the contact sets of said outgoing lines, a repeating coil associated with said link circuit, said repeating coil comprising a primary winding and a secondary winding, means variably responsive to said combinations of potentials to vary the ratio of the number of turns of said secondary winding to the number of turns of said primary winding, and means including an associated relay combination to move said combination of potentials from a contact set at a desired time.
25. 30. In a telephone exchange system, incoming lines, means to transmit voice currents over said incoming lines, outgoing lines, a link circuit to be used in establishing a connection between an incoming line and an outgoing line, a device associated with said link circuit, said device being arranged to modify voice currents received over an incoming line, means to adjust said device to vary the degree of modification of said voice currents, and means associated with said outgoing lines to cause the operation of said adjusting means.
10. 15. 20. 25. 30. 35. 40. 45. 50. 55.
- In witness whereof, I hereunto subscribe my name this 23 day of Aug. A. D., 1920.
- ALBEN E. LUNDELL.
